CONCRETE REINFORCING SUPPORT FOR TRAPEZOIDAL TROUGH

Robert J. Ilukowicz, Coram, N.Y., assignor to Preco
Industries, Ltd., Plainview, N.Y.

Filed July 30, 1975, Ser. No. 600,132

Term of patent 14 years

Int. Cl. D8—08

U.S. Cl. D8—228

FIG. 1

FIG. 3

FIG. 2

FIG. 4

FIG. 5

FIG. 6

FIG. 8

FIG. 7

FIG. 9

FIG. 10

FIG. 1 is a top plan view of a concrete reinforcing support for trapezoidal trough provided with a design in accordance with one embodiment of my invention;

FIG. 2 is a front elevational view;

FIG. 3 is a left end elevational view;

FIG. 4 is a right end elevational view;

FIG. 5 is a bottom plan view;

FIG. 6 is a top plan view of a concrete reinforcing support for trapezoidal trough provided with a design in accordance with a second embodiment of my invention;

FIG. 7 is a front elevational view;

FIG. 8 is a left end elevational view;

FIG. 9 is a right end elevational view; and

FIG. 10 is a bottom plan view.

The rear views are mirror images of the front view and are therefore, not shown.

I claim:

The ornamental design for a concrete reinforcing support for a trapezoidal trough, substantially as shown and described.
